DESIGN FOR A TABLE

Gordon C. Little, Los Angeles, Calif.

Application December 10, 1946, Serial No. 135,394

Term of patent 7 years

(Cl. D33—14)

To all whom it may concern:

Be it known that I, Gordon C. Little, a citizen of the United States, residing in Los Angeles, in the county of Los Angeles and State of California, have invented a new, original, and ornamental Design for a Table, of which the following is a specification, reference being made to the accompanying drawing, forming a part thereof.

Fig. 1 is a perspective view of a table, showing my new design, and

Fig. 2 is a bottom view of the same.

I claim:

The ornamental design for a table, as shown.

GORDON C. LITTLE.
